UNITED STATES PATENT OFFICE

LOUIS A. SUEKOFF, OF WILMETTE, ILLINOIS

SPRING ASSEMBLY FOR UPHOLSTERY

Application filed November 2, 1931. Serial No. 572,494.

This invention relates to improvements in spring assemblies for upholstery and has for its object to provide a simple, cheap, and efficient structure of this character which may be easily and cheaply incorporated into articles of furniture, such as chair frames, couch or davenport frames, and the like in such grouping or association as the manufacturer of furniture may desire.

More specifically stated, the invention has for its object to provide spring assemblies, each of which comprises a single strip of suitable material, such as sheet metal which is equipped with a row of fabric encased springs and equipped at its ends with means for securing the strip to a frame structure to provide the advantage to the furniture manufacturer of enabling him to dispose the said strips in closely or widely spaced relation to each other, and also slightly angularly to each other to provide a composite spring assembly of a shape best adapted to the shape of the frame element to be equipped with the said spring assembly.

A suitable embodiment of the invention is illustrated in the accompanying drawing, wherein:

Fig. 1 is a perspective view, partly broken away, showing a spring assembly constructed in accordance with the invention.

Fig. 2 is a fragmentary detail vertical section of the same.

Fig. 3 is a fragmentary sectional view similar to Fig. 2 showing a slightly modified form of construction.

Fig. 4 is a rear elevation of a chair-back equipped with a plurality of spring assemblies of the type shown in Fig. 1.

Fig. 5 is a view similar to Fig. 4 showing a modified form of construction of the spring assembly.

The structure of this invention includes a flat strip 1 of suitable sheet metal which may be of a thickness and width to render it only slightly flexible, or of a thinner and narrower stock having correspondingly greater flexibility.

The strip 1 is provided at regular intervals, longitudinally thereof and midway between its side edges, with perforations 2. The

number of said perforations 2 will be equal to the number, plus one, of springs to be mounted thereon, so that, if six springs are to be so mounted, there must be seven of said perforations 2.

The spacing of the perforations 2 from each other will be equal to the diameter of the springs to be mounted thereon.

A series of springs 3, of equal diameter and encased in a series of articulate fabric pockets or casings 4, is mounted on the strip 1. The said pockets or casings 4 are made of a single strip of fabric folded upon itself and provided with parallel stitch-chains 5 extending transversely of the fold in the said strip, thus forming a series of flat pockets into which the springs 3 are inserted with their longitudinal axes disposed transversely to the flat walls of said pockets.

A stitch-chain 6 extending transversely to the stitch-chains 5 and disposed adjacent to and substantially parallel with the edges of the walls of said flat pockets, serves to close the latter. The springs 3 are then turned in the pockets so that their longitudinal axes are parallel with the stitch-chains 5.

The said pockets or casings 4 are thus distended to cylindrical form and provide surplus material at the ends of the several stitch-chains 5 to form loose fabric projections 7.

The foregoing type of spring-filled casings is well-known in this art.

The said fabric projections 7 along one set of substantially circular end walls of the pockets or casings 4 are passed through the perforations 2 of the strip 1 and are secured against retraction by means of a suitable retaining device. The latter preferably consists of a wire 8 of a length somewhat in excess of the length of the articulate fabric spring-filled structure, said wire being passed successively through the projections 7 which extend through the perforations, and lies in close contact with the face of the strip 1 opposite that upon which the spring-filled casings rest, and thus firmly secures the latter to the strip 1.

The wire 8 is preferably provided at one end with a loop 9 formed thereon before the wire is inserted through the projecting por-

tions 7, and the other end of the wire is then bent to form a loop 10, said loops 9 and 10 serving to prevent withdrawal of the wire 8 from the said projecting portions 7.

Obviously, the same or substantially the same result will be secured by passing an individual retaining element through each of said projections 7 as, for example, a conventional safety pin or a cotter-pin.

10 The length of the strip 1 will be sufficiently greater than the length of the set or chain of spring-filled casings 4 mounted thereon as may be requisite and necessary to enable the ends of said strip 1 to be secured to opposed rails or portions of a furniture frame element, the opening in which is to be spanned by the said strip.

These end portions of the strip 1 will be provided with perforations 11, as shown in Fig. 1, to receive nails, screws, or other securing means, or, as shown in Fig. 3, will be provided with loop formations 12 to receive wires or rods for associating a series of the strips 1 to form a spring assembly consisting of a number of said strips 1 with their spring-filled casings 4.

Obviously, each of said strips 1 and its chain of spring-filled casings 4 constitutes an individual spring assembly. The great advantage of the invention lies in the fact that any desired number of these individual spring assemblies may be disposed side by side, closely or widely spaced from each other, to form a composite spring assembly of any desired area and of a great variety of shapes to fit the form of any furniture frame opening designed to contain a spring assembly.

A further advantage of the invention resides in the fact that a series of strips 1 carrying springs of one size, as, for example, springs four inches long and two and one-half inches diameter, may be easily associated with other strips 1 equipped with springs three inches long and of the same or other diameter, in a single composite assembly. Furthermore, strips 1 equipped with a series of six springs each, for example, may be associated with other strips 1 equipped with a greater or smaller series of springs each.

50 This flexibility of composition of an assembly to cover any desired area, as above pointed out, is very advantageous to the manufacturer of the spring assemblies as well as to the manufacturer of upholstered furniture in that the manufacturer of the spring assemblies may carry a great quantity of said assemblies in stock and thus obtain the advantage of lower cost of production. The furniture manufacturer may also purchase greater quantities of said assemblies than may be required for his immediate needs and thus secure the corresponding price advantage without fear of being obliged to discard surplus stock because of changes in design of furniture frames.

While I prefer to make the strips 1 of sheet metal, I desire it to be understood that said strip may consist of any other suitable material, said strip constituting a base or supporting web for the fabric encased springs, the invention residing more particularly in the means employed for securing the casings and springs to said web.

70 The supporting web may, obviously, be also provided of a width sufficient to receive two or more rows of spring-filled casings 4, without departing from the invention.

I claim as my invention:

1. A spring assembly comprising an articulate series of spring-filled fabric casings, a flat strip of sheet metal provided with a series of perforations spaced from each other a distance equal to the diameters of the springs in said casings, the latter having loose fabric portions at the ends of the meeting points of the several casings and at the extremities of the series thereof projecting through said perforations in said strip, and substantially non-elastic retaining means extending through said loose fabric portions and spanning said perforations on the face of the said strip opposite that upon which said casings are supported.

2. A spring assembly comprising a supporting web of suitable material, fabric spring-filled casings disposed on one face of said web, said casings presenting loose fabric portions at diametrically opposed points of their substantially circular ends and said web being provided with perforations through which said loose fabric portions project, and substantially inflexible fastening means disposed upon the other face of said web and passing through said loose fabric portions of said casings and spanning the perforations through which the said loose fabric portions project.

3. A spring assembly comprising a supporting web of suitable material, fabric spring-filled casings disposed on one face of said web, said casings presenting loose fabric portions at diametrically opposed points of their substantially circular ends and said web being provided with perforations through which said loose fabric portions project, and means disposed on the other face of said web and passing successively through a plurality of the projecting portions of said loose fabric and spanning the perforations through which the said loose fabric portions extend to secure the spring-filled casings to the web.

In testimony whereof, I have hereunto set my hand this 30th day of October, 1931.

LOUIS A. SUEKOFF.
